Attorney.

UNITED STATES PATENT OFFICE.

ZENAS COBB, OF CHICAGO, ILLINOIS.

DOOR-SPRING.

SPECIFICATION forming part of Letters Patent No. 240,811, dated May 3, 1881.

Application filed November 17, 1880. (Model.)

To all whom it may concern:

Be it known that I, ZENAS COBB, a citizen of the United States, residing at Chicago, in the county of Cook and State of Illinois, have 5 invented certain new and useful Improvements in Door-Springs; and I hereby declare the following to be a full, clear, and exact description thereof, reference being had to the accompanying drawings, of which—

10 Figure 1 is a horizontal section of a door and casing provided with my device; Fig. 2, a longitudinal section of the device itself, and Fig. 3 a detail view.

15 My present invention relates to certain improvements upon the door-spring for which Letters Patent of the United States No. 201,500 were granted to me March 19, 1878.

20 In my said former invention an arm or lever, attached by a bar to the jamb, operated to command 25 press a helical spring encircling a rod set into a suitable bed-plate screwed to the door, all as in my present device; but the construction was such that after the door had been opened to an angle of ninety degrees the tendency of 30 the spring was to push it still farther open instead of to close it. My object is to change this feature, so that the spring shall operate to shut the door until it has passed an angle of about one hundred and eighty degrees; and, 35 furthermore, to provide means whereby the device may be made to exert a greater or less force with the same spring, and thus be readily adapted to doors of different weights.

40 To these ends my invention consists, first, in connecting the short arm of the operating-lever, by means of a stirrup, to the end of the rod which passes through the spring; and, secondly, in providing the long arm of the said operating-lever with an extension at a 45 right angle, or nearly so, said extension having a series of holes for the adjustment to different positions of the bar which connects it to the jamb, all as hereinafter more fully set forth.

45 In the drawings, A is the bed-plate, adapted to be screwed to the door B, as represented in Fig. 1. This bed-plate is provided with two goose-necks, v, at one end, and with two more, v', considerably shorter than the first, at the 50 opposite end. The inner end or edge of each goose-neck is notched or recessed, as shown at u.

C is a lever provided with trunnions t, which rest in the notches u of the goose-necks v, to form a fulcrum, and D is the spring which surrounds a rod, E, having a head, F, with extension s, notched at its extremity. The spring is retained between the head F of the rod and a ring, G, through which the rod passes freely, and which is provided with trunnions t', which bear in the recesses u upon the inner edges of 55 60 goose-necks v'.

In my former Letters Patent, above referred to, the short arm of the lever C was pivoted immediately to the head F of the rod. The 65 obvious effect of that construction is to cause the spring to operate to shut the door only until the latter has passed the position indicated by the dotted lines in Fig. 1, when, the short arm having crossed the dead-center, the tendency of the spring is to send it in the other direction, and thus throw the door against the wall. While such an action is sometimes desirable, it is rather a disadvantage in a majority of cases. I accordingly now connect the 70 short arm of the lever C to the head of the rod by means of a link or stirrup, H, pivoted to each. The obvious effect of this construction is to cause the spring to force the said short arm in the same direction until the door has 75 been opened to an angle of one hundred and eighty degrees, or nearly so, and thus to operate at all intermediate angles to shut the door. For convenience of adjustment, the stirrup may be pivoted to the head F of the rod 80 by means of a pin, q, near the end of the stirrup, adapted to fit in the notch at the end of the extension s, as shown.

The second feature of my improvement lies in providing the long arm of the lever C with 85 an extension, I, at a right angle, or nearly so, with the said arm, and having a series of holes, p, through it, into any one of which the bar K may be hooked.

If it is desired to have the spring exert the 90 greatest possible force, the bar K is hooked into the hole over the end of the lever, corresponding to the construction shown in my said former Letters Patent. If the least force is required, the rod is hooked into the hole at the 95 extremity of the extension, and varying degrees of stiffness as to the action may be secured by hooking it into the intermediate holes. By moving the bar K from the end of the ex- 100

tension to the end of the lever (the position shown in my former patent) an increase of more than one hundred per cent. in the force of the spring is obtained, and so in proportion for intermediate points.

What I claim as new, and desire to secure by Letters Patent, is—

1. In combination with the bed-plate A, spring D, rod E, having the head F, and lever C, pivoted to the said bed-plate, the stirrup H, connecting the short arm of the lever C with the head F of the rod E, substantially as and for the purpose described.

2. In combination with the bed-plate A, spring D, and rod E, having the head F, the lever C, pivoted to the said bed-plate, and connected to the head of the rod E, and provided with the extension I, having holes p, said extension projecting from the outer end of the lever C at a right angle, or nearly so, with said lever, substantially as described.

ZENAS COBB.

In presence of—

GEO. N. MOORE,
FRANKLIN P. SIMONS.
